L. A. KING

TOY MOTION PICTURE DEVICE

Filed Aug. 4. 1924

UNITED STATES PATENT OFFICE.

LELAND A. KING, OF CHICAGO, ILLINOIS.

TOY MOTION-PICTURE DEVICE.

Application filed August 4, 1924. Serial No. 729,934.

To all whom it may concern:

Be it known that I, LELAND A. KING, a citizen of the United States, residing in Chicago, Cook County, Illinois, have invented certain new and useful Improvements in Toy Motion-Picture Devices, of which the following is a specification.

The present improvements relate to motion picture devices of the kind in which there is a rotatable member provided with pictures and sight openings through which the operator views the pictures by reflection from a mirror.

The chief object of the present improvements is to increase the efficiency of such devices to provide interest and amusement.

In the accompanying drawings, forming a part of this specification, Figure 1 shows a preferred form of the device in what may arbitrarily be termed a rear view; Fig. 2 shows the same device in what may similarly be called its front view; Fig. 3 shows a section of the device of Figs. 1 and 2 as on the broken line 3—3 of Fig. 1, this figure also showing how the device is normally used; Fig. 4 is a face view of a modified form of the device and Fig. 5 is a section through the device of Fig. 4 on the line 5—5 thereof.

Referring to Figs. 1 to 3 inclusive the structure illustrated includes a disc-like member 10 which may be of cardboard or other thin sheet material, and a supporting member 11, also preferably of thin sheet material, the disc 10 being pivotally mounted, as by an eyelet 12, upon the support. The supporting member 11 is positioned face to face with the disc and substantially overlies the disc on one of its sides, but, as will be noted, the edge of the disc extends beyond the edge of the support whereby the disc may readily be contacted by a finger of the operator and rotated by a sharp brushing or flicking movement of the hand. The supporting member is extended sufficiently, preferably at the bottom, to provide means for holding it between the finger and thumb of the operator's other hand.

The disc 10 has pictures on both of its sides, which pictures are such as to give the effect of action or motion when the device is normally in use. The ones shown in Fig. 1 produce the effect of flopping a pancake over from a pan, while those shown in Fig. 2 show a hog or hogs in the act of leaping.

The disc 10 has a plurality of sight-openings 13 circumferentially spaced apart and

preferably arranged near the margin of the disc. To produce the desired effect there is a relationship between the pictures and the sight-openings as 13, which relationship varies according to the pictures or desired effect, is well understood in the art, and requires no description here. This cooperative relationship exists with respect to the pictures on both sides of the disc 10 in the present device.

The supporting member 11 is shown as having a pair of sight-openings 14 spaced apart horizontally the average normal width between the eyes of a person, and are so positioned as to register respectively with sight openings 13 in the disc 10. The optical effect of motion in the pictures would be produced with only one sight opening as 14, but it is preferable to have two for better vision. The arrangement of the sight openings 13 and 14 is such that the operator looks through two sight openings 13 simultaneously, the distance between the sight openings 14 corresponding to that between 70 adjacent ones of the sight openings 13.

The supporting member 11 is provided with an exposure opening 15 through which the pictures on the side of the disc-like member facing the supporting member may be exposed. This opening as 15 may have various shapes according to the picture to be exposed thereat. The construction in this respect has the important function of blocking out or concealing from view pictures other than the particular one to be viewed at a given instant, and, while the material surrounding the opening 15 is relatively stationary, the effect is very much like that of a shutter in that only a single picture is in full view at each particular moment of operation. According to Fig. 1 the figure illustrated stands out as a single individual flopping the pancake, while according to Fig. 2 the operator sees a plurality of hogs,

all in action, jumping over the obstruction. For some kinds of pictures the shutter-like effect according to Fig. 1 is preferable, while for others, as in Fig. 2, the interest is probably heightened by the impression of a number or series of things in action.

That part of the supporting member 11 contiguous to the sight openings 14 may be termed a shield overlying a portion of the disc-like member and having a sight-opening or openings therein. By covering the pictures on the rear side of the disc 10 at the

sight-openings 14 some confusion to the eye is avoided. I preferably provide a darkened area, as 16, adjacent to the sight-openings 14 and a darkened area 17 adjacent to the sight-openings 18 on both sides of the disc 10 for comfort to the eye of the operator and for better picture effects. This feature in devices of this general character is claimed in my Patent No. 1,526,794, Feb. 17, 1925.

Referring to Figs. 4 and 5 the disc 20 is to be considered as having pictures on both sides thereof, for instance the same pictures as are shown on Figs. 1 and 2. The supporting member 21 may be considered to be of thin sheet metal bent upon itself, the disc 20 being rotatably mounted, as upon an eyelet 22, between the sides of the supporting member 21. The marginal sight openings 24 and the relatively fixed sight openings 23 may be considered in all respects in accordance with sight openings 13 and 14 respectively in the other figures. The shield portion 21^a is shown as being the same on both sides, and the oppositely-disposed sight openings 23 are in alignment with each other and with the sight openings 24 as they successively reach the openings 23.

The mirror as 30 reflects the pictures to the eye whichever side of the device is turned theretoward.

I contemplate as being included in the present invention such modifications of and departures from what is herein specifically illustrated and described as fall within the scope of the appended claims.

I claim:

1. In a motion picture device of the character described, the combination of a flat disc-like member having circumferentially-spaced-apart sight openings and having pictures on both sides operatively positioned in relation to said sight openings for motion picture effects, a supporting member on which the disc-like member is rotatably mounted, the supporting member having a shield part face to face with the disc-like member, said shield part being of insufficient extent to cover the disc-like member whereby some picture matter on the disc-like member faced toward the supporting member is exposed to view while other of such matter is covered by the shield part, the shield part having a sight opening registering successively with the sight openings in the disc-like member when the latter is rotated, the arrangement being such that the opera-

tor may look in either direction through the registering sight openings toward a mirror and obtain motion picture effects by reflection of the pictures on the side of the disc-like member facing the mirror. 60

2. In a motion picture device of the character described, the combination of a flat disc-like member having marginal sight 65 openings circumferentially-spaced-apart and having pictures on both sides operatively positioned for motion effects in relation to said sight openings, a supporting member on which the disc-like member is rotatably mounted, the supporting member having a part face to face with the disc-like member and overlying the disc-like member only partially whereby a picture on the disc-like member faced toward the supporting member is exposed to view, said part of the supporting member having a sight opening registering successively with the sight openings in the disc-like member when the latter is rotated, the arrangement being such 70 that the operator may look in either direction through the registering sight openings toward a mirror and obtain motion picture effects by reflection of the pictures on the side of the disc-like member facing the 75 mirror. 80

3. In a motion picture device of the character described, the combination of a flat disc-like member having pictures for motion 90 effects on both sides thereof, a supporting member upon which the disc-like member is rotatably mounted, the supporting member having a part substantially overlying the disc-like member on one side thereof and having a picture-exposure opening therein 95 whereby successive pictures on the disc-like member may be exposed thereat, the disc-like member having a plurality of circumferentially-spaced-apart sight openings therein cooperatively arranged for motion 100 picture effects with the pictures on both sides of the disc-like member, the supporting member having a sight opening registering successively with the sight openings in the disc-like member when the latter is rotated, the arrangement being such that the operator may look in either direction through the alining sight openings toward a mirror when the disc is rotated relative 105 to the supporting member and obtain motion picture effect by reflection of the pictures on the side of the rotatable member facing the mirror. 110

LELAND A. KING.
